UNITED STATES PATENT OFFICE.

WILLARD D. McFALL, OF EAST ORANGE, NEW JERSEY.

FILING OR INDEXING APPLIANCE.

Application filed October 2, 1925. Serial No. 60,040.

This invention relates in general to filing and indexing systems and appliances, and more particularly to a system and appliance for filing cards, envelopes or the like.

6 One object of the invention is to provide a novel and improved system and appliance for filing cards and envelopes whereby a misplaced or improperly filed card or envelope may be easily and quickly located in the file 10 box, drawer or other container, without the necessity of examining each envelope or card in the box or drawer.

Another object is to provide a novel and improved set of cards or envelopes which 15 embody features of construction whereby a misplaced or improperly filed card or envelope can be quickly located at any point in the set without individually examining each card or envelope.

20 Further objects are to provide such a filing system and appliance embodying a novel and improved set of cards or envelopes and an index member to cooperate therewith; to provide a filing or index system comprising 25 a set of cards or envelopes divided into a plurality of series or groups, said cards or envelopes embodying novel and improved features of construction whereby each is identified with its particular group and distinguished from all other groups, and to obtain other results and advantages as may be brought out by the following description.

For the purpose of illustrating the principles of the invention, in the accompanying drawings I have shown the same applied to a known filing system, but it will be understood that the invention is susceptible of use in connection with other filing systems without departing from the spirit or 30 scope of the invention.

40 Referring to said drawings, in which corresponding and like parts are designated throughout the several views by the same reference characters,

45 Figure 1 is a perspective view of a file drawer and a plurality of envelopes for classifying and filing information or data, and

50 Figure 2 is a perspective view of one of the envelopes.

The system of filing illustrated comprises the use of a file box, drawer or like container 1 and a plurality of envelopes or 55 folders 2 which are adapted to receive papers or other data 3 and be placed in the drawer

or box 1 in numerical order, each of the envelopes or folders including an indexing or designating inscription 4 which in the present instance is a number. This type of filing appliance is extensively used by insurance 60 companies, and a large number of the envelopes 2 are used and filed away in several boxes or drawers. The usual type of container for the envelopes is a drawer such as illustrated, which includes a front wall 5, 65 side walls 6 and bottom 7, the envelopes being placed in the drawer endwise and held in an upright position by an adjustable follower (not shown) common to filing drawers.

It frequently happens that an envelope is 70 misplaced or improperly filed, and in order to locate the envelope it is necessary to examine each of the envelopes in all of the filing drawers until the misplaced one is found. Obviously, where the number of envelopes runs into the hundreds of thousands, 75 the search for a misfiled one is often the cause of much loss of time. It is to overcome these objections to the present filing systems and appliances that the present invention is directed.

In accordance with the invention, the envelopes 2 are divided into groups or series. In the present embodiment of the invention illustrated, each group comprises one hundred envelopes, and it is possible to locate 85 any of the one hundred envelopes of any group should it be misplaced in any of the other groups. It would be possible to adapt the invention to use with groups of less envelopes than one hundred, but in practical 90 operation of the filing system it is not much of a task to examine one hundred envelopes to locate a misfiled one within the particular group. 95

Adjacent one edge of each envelope in each group is formed an opening 8, said opening representing the hundred digit of the envelope number, in the present instance the "700" in the envelope number "632799". 100 Each envelope in the seven hundred group, that is each envelope numbered from 700 to 799, inclusive, has a similar opening arranged in a position on the corresponding envelope identical with the opening 8 on 105 the others 2. The envelopes in the eight hundred group have a similar opening 9 which is arranged in a slightly different position upon the corresponding envelope, so that when the seven hundred and eight 110

hundred groups are arranged in packed relation, the openings 8 and 9 are out of alinement, as shown in Figure 1. Similarly, there is a corresponding opening in each one hundred group of envelopes, the positions of the openings in the respective groups being different. Each envelope is also provided with an opening 10 which represents the thousands digit in the envelope number 10 in the present instance the "2" in the envelope number "632799". The openings in the next thousand group, that is in the "3000" group, would be positioned on the respective envelopes differently from the opening 15 10. In a similar manner, each envelope is formed with openings 11 and 12 which represent the tens of thousands and hundreds of thousands digits, respectively. Accordingly, each envelope in the group 20 numbered 632700-632799 would have openings 8, 10, 11 and 12 in identical positions; the group of envelopes numbered 632800-632899 would have openings 10, 11 and 12 in identical positions with the openings 10, 25 11 and 12 in the other group, but the openings 8 and 9 in the two groups will be in different positions. Also, the envelopes in the 640000 group will have the opening 11 in a different position from the corresponding 30 openings in the group numbered 630000, and the group numbered 631000 would have the opening 10 in a different position from the corresponding opening in the group 632000. Therefore, when the various groups 35 of envelopes are arranged in their proper order in packed relation, as shown in Figure 1 of the drawings, the four openings 8, 10, 11 and 12 in all envelopes of the same group will be in alinement. Should a card from 40 one group be improperly filed in another group, at least one of the openings of the misfiled card will be out of alinement with the corresponding openings of the cards in the group in which it is misfiled, and should 45 a rod or wire, such as indicated at 13, be inserted into all of the openings in the cards, its passage entirely through one of the openings will be prevented by the misfiled card which can thus be easily located, as shown 50 in Figure 1 of the drawings. In case the insertion of the rod 13 should be interrupted by the first card in another group, as shown in Figure 1, the rod can then be inserted from the other end of the pack to locate any 55 card which might be misfiled in the second-mentioned group.

It is relatively immaterial in what position the openings 8, 10, 11 and 12 are located on the envelope, and the shape of the 60 openings is also immaterial. Where the envelopes are filed in a drawer, as shown, it is preferable to have the openings arranged in two vertical rows which are laterally spaced.

65 To facilitate in the location of a mis-

placed card and in the filing of the envelopes generally, the front 5 of the drawer is preferably formed with four series of openings lettered A, B, C, D, respectively, the openings being numbered from 0 to 9 in each 70 series. The series A corresponds to the hundreds of thousands digit in the envelope numbers, the series B corresponds to the tens of thousands digit, the series C corresponds to the thousands digit and the series D to the 75 hundreds digit. Each of the openings in each of the series is disposed in position to aline with the corresponding opening in the cards; for instance the opening 6 in series A is in alinement with the openings 80 12 in the cards of the 600000 group, while the opening 7 in the D series is in alinement with the openings 8 in the cards of the seven hundred group. The openings of the series A, B, C and D accordingly serve as indexes 85 for the insertion of the rod 13 for locating a misplaced card, the operator being first apprised of the range of numbers of the envelopes in the drawers by any suitable means, such as an inscription 14 on the front of the 90 drawer.

If a search is to be made for a misplaced card in the drawer illustrated, the rod 13 would be successively inserted into the opening 7 of series D, the opening 2 of the 95 series C, the opening 3 of the series B and the opening 6 of the series A.

It is not essential that the drawer front be utilized as the index member, since a separate box or container constructed similarly to the drawer could be utilized by successively removing all of the envelopes from the file drawers and placing them into a special drawer for the searching operation, after which the envelopes would be replaced 105 in their proper file drawer.

It will be noted that not only does the system and appliance enable a card in the wrong place in the box or drawer to be located, but a card which has been filed upside down or facing rearwardly may also be 110 easily located.

Any other desired system of indexing than the number system above described may be utilized without departing from the spirit 115 of the invention, and other indicators than the openings 8, 10, 11 and 12 may also be utilized, for instance notches. Also, the openings might be arranged at the tops or bottoms of the cards instead of at the sides as 120 illustrated. Furthermore, the invention is susceptible of use in connection with filing systems in which the filing media is other than cards or envelopes, and the term "information cards" in the appended claims is 125 intended to include all adaptable filing media.

Accordingly, while I have shown and described one preferred embodiment of the invention, I do not desire to be understood 130

as limiting myself except as required by the following claims when construed in the light of the prior art.

Having thus described the invention, what

5 I claim is:

- 3.1 claim is.

1. A plurality of series of information cards, each card of each series having a plurality of openings, all of the cards of each series having certain openings located identically with each other and with corresponding openings of the other series and another opening located differently from the corresponding openings of the other series, so that when said cards are placed in a packed relation all the openings of all the cards in one series will be in alinement with each other and at least one opening of each card of each series will be out of alinement with the corresponding openings of the cards of the other series, whereby said openings may serve to indicate different series and as a signal should a card of one series be misfiled in another group, each card of each series having a different designating inscription composed of a plurality of characters and each of the openings representing one of said characters, the characters so represented being the same for all of the cards of the same series.

2. A plurality of series of information cards, each card of each series having a plurality of openings, all of the cards of each series having certain openings located identically with each other and with corresponding openings of the other series and another opening located differently from an opening of the other series, so that when said cards are placed in a packed relation all the openings of all the cards in one series will be in alinement with each other and at least one opening of each card of each series will be out of alinement with the corresponding openings of the cards of the other series, each card of each series having a different designating inscription composed of a plurality of characters and each of the openings representing one of said characters, the characters so represented being the same for all of the cards of the same series, an index member at the front of the pack of cards and having a plurality of series of openings each series corresponding to one of the openings in each of said cards and each opening in each of said series on the index member being in alinement with one of the openings in a series of the cards and having the same designating character as that represented by the corresponding opening in the cards, and a car-finding member to be inserted through said openings in said index member and the corresponding openings in said cards to locate a misplaced card.

3. An information card file, comprising a plurality of groups of information cards all cards and the other indicator located differently than the corresponding indicators of the cards in the other groups, each of said cards having a different designating inscription composed of a plurality of characters, and each of said indicators representing one of said characters, whereby said indicators serve to indicate different groups and as a signal should a card of one group be misfiled in another group.

4. A plurality of series of information cards, each card of each series having a plurality of openings, all of the cards of each series having certain openings located identically with each other and with corresponding openings of the other series and another opening located differently from the corresponding openings of the other series, so that when said cards are placed in a packed relation all the openings of all the cards in one series will be in alinement with each other and at least one opening of each card of each series will be out of alinement with the corresponding openings of the cards of the other series, whereby said openings may serve to indicate different series and as a signal should a card of one series be misfiled in another group, each card of each series having a different designating number composed of a plurality of figures and each of said openings representing one of said figures, said cards being consecutively numerically arranged.

5. A plurality of series of information cards, each card of each series having a plurality of openings, all of the cards of each series having certain openings located identically with each other and with corresponding openings of the other series and another opening located differently from the corresponding openings of the other series, so that when said cards are placed in a packed relation all the openings of all the cards in one series will be in alinement with each other and at least one opening of each card of each series will be out of alinement with the corresponding openings of the cards of the other series, whereby said openings may serve to indicate different series and as a signal should a card of one series be misfiled in another group, each series of cards including one hundred cards which have different consecutive designating numbers each comprising a plurality of figures and each of said openings representing one of said figures, the figures so represented being the same for all the cards of the same series, said cards being consecutively numerically arranged, an index mem-

ber at the front of the pack of cards and having a plurality of series of openings each series corresponding to one of the openings in each of said cards and each opening in each of said series on the index member being in alinement with one of the openings in a series of the cards and having the same des-

ignating figure as that represented by the corresponding opening in the cards, and a card-finding member to be inserted through said openings in said index member and the corresponding openings in said cards to locate a misplaced card. ¹⁰
